UNITED STATES PATENT OFFICE.

HORACE C. STANTON, OF PHELPS, NEW YORK.

INDIVIDUALIZED KEYBOARD FOR TYPE-WRITING MACHINES.

SPECIFICATION forming part of Letters Patent No. 726,107, dated April 21, 1903.

Application filed August 29, 1901. Serial No. 73,637. (No model.)

To all whom it may concern:

Be it known that I, HORACE C. STANTON, a citizen of the United States, residing at Phelps, in the county of Ontario and State of New York, have invented certain new and useful Improvements in Individualized Keyboards for Type-Writing Machines, of which the following is a specification.

This invention relates to type-writing machines, and has special reference to an improved keyboard embodying means for facilitating the manipulation of the keys by the touch method.

To this end the invention primarily contemplates individualizing the keys of a type-writing machine keyboard by imparting thereto some peculiar form or characteristic independent of the characters thereon and also grouping adjacent keys or key-tops in such a way that the different keys may easily and with facility be distinguished and selected by the touch rather than by sight, thus specially adapting the keyboard for the use of the blind, as well as for the use of quick operators, depending largely upon the touch method for the manipulation of the keys.

There is a disposition among experts to learn to operate type-writing machines by touch alone, without looking at the keys, as the touch method when thoroughly mastered enables an operator to manipulate the keys much more rapidly and equally as accurately as when the sight is depended upon to distinguish one key from another by the character thereon. It is recognized that to master the keys rapidly and correctly solely by the touch method is an exceedingly delicate, difficult, and tedious accomplishment, and with the construction of keyboards heretofore used and patented it is almost impossible to do this with accuracy, as if an operator becomes careless even for an instant or inadvertently changes his position the location of the keys becomes readily lost. However, the present invention of the individualized touch-keyboard entirely obviates this difficulty by providing an improved arrangement of variously-shaped key-tops, whereby the fingers learn to recognize each peculiar key instantly, thus enabling

the operator, by the peculiar form of each individual key, to strike it with absolute accuracy. The invention is therefore not only

well adapted for the use of the blind on account of the keys being more quickly and accurately distinguished than by the use of raised characters or other expedients heretofore resorted to, but may also be advantageously adopted by beginners and experts alike on account of the general advantages of the touch method. For the latter class of persons the keyboard possesses many advantages, since all of the keys or key-tops are doubly distinguished—namely, both by appearance and by form.

In carrying out the above objects it may be stated generally that a characteristic feature of the invention resides in making the keys or key-tops of such distinctive forms that the fingers recognize them by mere feeling, so the operator without looking at them may readily and accurately find and strike each and every key by touch alone. In this connection it should be stated that the invention involves as an essential feature thereof a diversity of form or shape among adjacent keys and such a disposition of these variously-shaped keys that two of the same form never come together among the keys that are struck by the same hand. Also the invention contemplates arranging the variously-shaped keys in special distinguishing positions to facilitate locating different keys from other keys, which may be properly termed "cue" or "guide" keys.

With these and many other objects in view, which will more readily appear as the nature of the invention is better understood, the same consists in the novel combination and arrangement of elements hereinafter more fully described, illustrated, and claimed.

The essential or characteristic features of the invention, as above indicated, are necessarily susceptible to a wide range of modification without departing from the spirit or scope of the invention; but a preferred embodiment thereof is shown in the drawings, in which—

Figure 1 is a perspective view of the left-hand half of a universal keyboard, such as employed on the "Smith Premier" and similar type-writing machines, illustrating the preferred means of carrying out the invention with such keyboard. Fig. 2 is a detail perspective view of a series of three keys or

key-tops for small letters, illustrative of the different shapes that may be resorted to, as well as illustrating the diversified arrangement of adjacent keys, said figure showing 5 the group of small letters, which in the correct system of type-writing are operated by the little finger of the left hand. Fig. 3 is a similar view of another group of keys which should be properly operated by the ring-finger 10 of the left hand, illustrating other diversified forms of keys, as well as showing very plainly the use of a certain key as a cue or guide key for those adjacent thereto. Figs. 4 and 5 are similar views showing the remaining small- 15 letter keys operated, respectively, by the middle and forefinger of the left hand. Fig. 6 is a similar view showing a group of keys of capital letters which are operated also by the little finger of the left hand.

20 Like numerals of reference designate corresponding parts in the several figures of the drawings.

The present invention is not intended to comprehend the class of keyboards heretofore designed for the touch method of type- 25 writing and does not include key-tops having raised or elevated characters, but, on the contrary, has in view such a diversified formation and arrangement of the individual keys as 30 to make the keyboard distinctively different from any of the methods heretofore resorted to, such as the employment of simple projections upon the keys or the alternating arrangement of smooth and rough keys, as already 35 disclosed in the art. Furthermore, the invention does not comprehend spacing-keys or shift-keys and the like, but embodies principally all keys printing capital and small letters, numerals, punctuation-marks, com- 40 mercial signs, the parentheses, the underscore, and, in fact, all characters which appear on what is commonly known as the "universal keyboard" with all its improvements.

45 Generally speaking, the invention involves, first, a diversity of form or shape among the individual or different keys of the keyboard entirely independent of the letter, numeral, or other character which may appear on the 50 key or key-top. For example, some keys or key-tops are concave and others convex, while, again, a key of either of these types may have its edge smooth or serrated, forming a rosette-like structure. Also some keys may 55 have depressions or indentations into which the finger readily sinks and by means of which the same are instantly identified, while other keys may have slight projections or elevated beads to arrest the finger and may also have 60 grooves of different depths running in different directions across the face of the key or key-top. These and many other identifying 65 details of form or shape may be resorted to in order to make the key of an individual diversified form, and consequently the invention is not limited to any of the specified forms of key-tops disclosed nor to the par-

ticular combinations pointed out, as it may obviously include an indefinite number of other forms as well as divers combinations. 70 It is only essential, first, that the keys be individually of a diversified form or shape, and, secondly, there must be a diversified arrangement of the individual keys—that is, such a disposition of the same that two of exactly 75 the same form never come together among the keys that are struck by the same hand.

The keys or key-tops are designated by the numeral 1 in the drawings, and it is of course understood that the same may be constructed 80 in any of the well-known ways and of any material, may be made of any color or colors, thereto in any suitable way. However, in order and also may have the characters applied to more clearly indicate the individually-dif- 85 ferent shape and the diversified arrangement of the keys there are shown in Figs. 2 to 6, inclusive, of the drawings a number of keys grouped together according to the correct method of type-writing, so reference will be 90 now made to these figures.

In Fig. 1 of the drawings there is illustrated the left-hand half of a universal keyboard embodying all of the keys which should be properly manipulated by the left hand of the 95 operator, and since the right-hand half, which is operated by the other hand, necessarily embodies the same characteristics it has been deemed sufficient for illustrative purposes to confine the illustration to that shown in Fig. 100 1. Referring more in detail to the characteristics of the individual keys and their diversified arrangement, there are shown in Fig. 2 of the drawings three keys or key-tops for small letters, which in the correct method 105 of manipulation should be operated by the little finger, the keys shown in Fig. 2 being designed, respectively, for the small letters "q," "a," and "z." Referring to this particular group of keys, according to the touch 110 method the rule is to keep the little finger on or over "a," which is therefore the cue or guide key, and while this key may be variously shaped or formed the same is illustrated as being slightly concaved at the top and 115 formed with a serrated or scalloped edge 2, thus producing a concave rosette-like structure. As no other key in the same vicinity has the same form, key "a" can be at once distinguished. In the group being referred 120 to the "q" key is located just above the "a" key, and the "z" key is located just below the "a" key. Said keys "q" and "z," while being of any desired form, may retain the usual form of the type-writer key with a slight 125 dish or concave at the top, inasmuch as working from the cue or guide key "a" the "q" and "z" keys can be readily located.

In Fig. 3 of the drawings is shown the group of small-letter keys which should be struck 130 by the ring-finger, which has little, if any, lateral play and is the most inflexible and awkward of all the fingers. Therefore this group of keys is preferably shaped so as to

materially aid the manipulation of the ring-finger. For instance, the central key of the group, the letter "s," is shown as provided with a broad transverse groove 4, while the 5 keys for the letters "w" and "x," respectively above and below the "s" key, are formed in their top faces with horseshoe-shaped depressions or seats 5, the open sides of which face toward the central key "s," and consequently 10 these three forms of keys make a sort of track or groove in which the finger readily moves up or down, thus identifying each key with facility. However even these details may be 15 changed in the practical carrying out of the invention.

In Fig. 4 of the drawings is shown a group of keys for the small letters "e," "d," and "c," designed to be struck by the middle finger. The central of said keys for the letter "d" is 20 provided upon diametrically opposite sides with indentations 6, while the keys "e" and "c," respectively above and below the same, may be of a plain rosette form with simply 25 serrations or scallops 7 at the edges thereof.

25 The forefinger of the hand, which is the most flexible of all the fingers, should properly manipulate six keys in the small letters being referred to—namely, "r," "f," "v," "t," "g," and "b." In the group of letters 30 "r," "f," and "v" the central key "f" is shown provided with a transverse groove 8, running in a different direction from the groove in the key "s," while the keys "r" and "v," respectively above and below the 35 same, may be of plain convex form, as shown. In the other group "t," "g," and "b" the central key "g" may be of the convex rosette type, although it will be understood that any other construction and relation of forms may 40 be utilized in this connection.

An extended explanation of the capital letters is unnecessary, as the keys therefor are distinguished substantially in the same manner as the corresponding small letters, and 45 each capital is struck with the same finger that strikes the corresponding small letter, although other special cues may be utilized to help the fingers coming up from the lower bank of keys to find the capital letters. For 50 instance, in Fig. 6 of the drawings is shown

a group of keys for the capital letters "Q," "A," and "Z." The upper key "Q" is slightly concave at the top, but is provided on the lower left-hand side with an indentation 9, into which the little finger naturally 55 and instantaneously fits. The lower key "Z" of the same group is similarly constructed, but is so remote from "Q" as not to be confused with it, while the central key "A" may be of the plain concave rosette form 60 and act in the capacity of a cue or guide key.

The same general thought, as above indicated, is carried throughout the entire keyboard, and it is therefore thought that the invention will now be fully understood without 65 further description. It is also understood, in view of the explanation, that various changes in the form, proportion, and minor details of construction may be resorted to without departing from the spirit or sacrificing any of 70 the advantages of the invention.

As will be understood, the keyboard herein described is obviously applicable to type-making, type-setting, or analogous machines embodying a type-writer keyboard. 75

Having thus described my invention, what I claim as new, and desire to secure by Letters Patent, is—

1. A keyboard for type-writing machines having keys of distinguishing physical characteristics and different groups of which are of like form, said keys of like form being separated or remote from each other. 80

2. A keyboard for type-writing machines comprising keys of individually - different 85 form or shape, having a diversified arrangement, and including cue or guide keys for those adjacent thereto.

3. A keyboard for type-writing machines comprising keys of individually - different 90 form or shape, having a diversified arrangement and grouped in sets, each set of keys including a cue or guide key for those adjacent thereto.

In testimony whereof I affix my signature 95 in presence of two witnesses.

HORACE C. STANTON.
